A. M. SUND

FLUID DISPENSER

Filed March 26, 1923

Inventor
Archie M. Sund

Attorneys

UNITED STATES PATENT OFFICE.

ARCHIE M. SUND, OF MINNEAPOLIS, MINNESOTA.

FLUID DISPENSER.

Application filed March 26, 1923. Serial No. 627,539.

To all whom it may concern:

Be it known that I, ARCHIE M. SUND, a citizen of the United States, residing at Minneapolis, in the county of Hennepin and State of Minnesota, have invented a new and useful Fluid Dispenser, of which the following is a specification.

My invention relates to improvements in fluid dispensers.

Its object is to provide a durable and inexpensive dispenser for fluids having a valved outlet, the valve mechanism being adapted to be actuated by a receptacle into which fluid is to be drawn.

A further object is to supply a sanitary dispenser of the present nature, wherein the escaping fluid is free from contact with the valve actuating mechanism, said dispenser having a limited number of separable parts adapted to be quickly and easily disassembled for cleansing purposes and reassembled for use.

Another object is to simplify the construction of a fluid dispenser including a normally sealed container by employing the air vent as a guide for the valve actuating mechanism.

With the foregoing and other objects in view, which will appear in the following description, the invention resides in the novel combination and arrangement of parts and in the details of construction hereinafter described and claimed.

In the drawings, Fig. 1 is a vertical, central, sectional view of a dispenser embodying my invention and Fig. 2 is a sectional view in detail taken on the line 2-2 of Fig. 1.

The embodiment shown in the drawing, 40 includes a jar A, a cap B and a bracket C. The jar A is formed with a neck 10 having external threads 11 thereon. The cap B consists of a closure piece 12 formed with an annular flange 13 thereon, the portion of said flange remote from said closure piece 12 being enlarged as at 14 to form a handhold for purposes soon to appear. The restricted annular portion of said flange adjacent to the closure piece 12 is pressed or otherwise formed to supply internal threads 15 and external threads 16, the former being designed to fit the threads 11 on the neck 10 of the jar A. The bracket C comprises an attaching plate 17 and a ring 18 reaching horizontally therefrom, said ring being threaded internally to re-

ceive the external threads 15 on the cap B and hold the assembled jar and cap in inverted position, as shown in Fig. 1. A funnel-like spout 19 is applied to the cap B and supplies an outlet for fluid contained within the jar A. A ball valve 20 fits within the tapered seat 21 in said spout and normally obstructs the same. A tube 22 carried by the cap B opens therethrough into the outer air and projects into the jar above the high liquid level therein, the length of said tube being only slightly less than the depth of the jar. A U-shaped valve stem D is provided, the branch 23 thereof being guided in the tube 22 and the branch 24 thereof being fastened at its extremity to the ball valve 20. A spring 25, anchored at one end to the cross member or head 26 of the valve stem, bears against the jar A and operates to yieldingly seat the valve member 20. A tripping member E is secured to the extremity of the valve stem branch 23 and is adapted to be engaged by a cup 27 or other receptacle into which fluid is to be drawn from the dispenser. Said tripping member E includes a shank 28 having an internally threaded bore which receives the contracted threaded end 29 of the branch 23. An arm or abutment 30 swings on a pivot 31 in the shank 28, a leaf spring 32 on the shank being arranged to engage right angular portions 33 and 34 on said arm adjacent to the pivot 31. This spring 32 in co-operating with the portion 33 holds the arm 30 at right angles with respect to the shank 28 and, in co-operating with the portion 34, holds said arm in alignment with the shank 28 in the same manner as a jack-knife blade is held with respect to its handle. With the arm 30 at right angles to the shank (Fig. 1), it occupies normal operative position. A receptacle into which fluid is to be drawn is held beneath the spout 19 and pressed upward against the arm 30. This pressure, operating against the action of the spring 32, lifts the valve 20 from the valve seat 21, thus permitting the fluid to escape through the spout and flow into the receptacle. When the desired quantity of liquid has been drawn from the dispenser, the pressure of the receptacle against the arm 30 is relieved, whereupon the valve 20 is reseated. When said valve 20 is lifted from its seat, objectionable swinging movements of the valve stem D

is prevented by means of valve guiding lugs 32 (Fig. 2) rising from the valve seat 20.

To refill the jar, the assembled jar and cap are removed from the bracket C, by unthreading the cap from the ring 17, through the medium of the handhold 13. After turning the jar A end for end and removing the cap B a new charge of liquid is poured into the jar, said cap being thereafter replaced on the jar. The jar is then inverted, the cap B being re-threaded in the supporting ring 17.

In cleansing the device, the valve stem D, which is normally carried by the cap B, may be detached from said cap by first swinging the arm 28 into alignment with the branch 22 and withdrawing the same from the tube 21, or by first unthreading the shank 27 from said branch 22.

20 Changes in the specific form of my invention, as herein disclosed, may be made within the scope of what is claimed without departing from the spirit of my invention.

25 Having described my invention, what I claim as new and desire to protect by Letters Patent is:

1. A liquid dispenser comprising a jar, a cap fitting the open end thereof, means for supporting the jar in upright inverted position, an outlet issuing from said cap, a valve member for obstructing said outlet, a vent tube carried by the cap and opening through the same and above the high liquid level within the jar, a U-shaped valve stem, one branch thereof being connected with the valve member and the other branch reaching through said tube, and a trip arm on the lower end of said last mentioned branch adapted to be actuated by a receptacle held in position to receive the flow from said outlet, said arm having a pivotal connection with said branch and capable of being swung from normally operative angular relation with respect thereto into alignment with said branch to permit of its ready removal from said tube.

2. A liquid dispenser comprising a jar, a cap fitting the open end thereof, means for supporting the jar in upright inverted position, an outlet issuing from said cap, a valve member for obstructing said outlet, a vent tube carried by the cap and opening above the high liquid level within the jar, a U-shaped valve stem, one branch thereof being connected with the valve member and the other branch reaching through said tube, and a trip member on the extremity of said last mentioned branch adapted to be actuated by a receptacle held in position to receive the flow from said outlet, said trip member having a jack-knife pivotal connection with said branch permitting of nor-

mally fixed angular relation between the trip member and said branch and aligned 65 relation between the same, the latter condition permitting of ready withdrawal of said branch from said tube for cleaning purposes.

3. A liquid dispenser comprising a jar, a cap fitting the open end thereof, means for supporting the jar in upright inverted position, an outlet issuing from said cap, a valve member for obstructing said outlet, a vent tube carried by the cap and opening 70 above the high liquid level within the jar, a U-shaped valve stem, one branch thereof being connected with the valve member and the other branch reaching through said tube, and a trip member on the extremity of 75 said last mentioned branch adapted to be actuated by a receptacle held in position to receive the flow from said outlet, said trip member being removable from said branch 80 to permit of the withdrawal of said branch 85 from said tube.

4. A liquid dispenser comprising a jar having an externally threaded neck, a bracket for supporting the jar in upright inverted position, said bracket including a 90 horizontal, internally threaded ring, a cap for the jar including an annular flange threaded internally to fit said neck and externally to fit within said ring, the margin of said flange being accessible above said ring and serving as a handhold for manipulating the cap, a spout issuing from the cap, a valve member for obstructing the flow of liquid from said spout and means for actuating said valve member.

5. A liquid dispenser comprising a bracket, a container, a removable closure for an opening therein, said closure being removably applicable to said bracket, a spout issuing from said closure, a valve member to obstruct the spout, a tube carried by the closure and reaching upward into the container above the high liquid level therein and a valve tripping device including a branch housed by said tube and accessible 100 for actuation beneath the structure.

6. A liquid dispenser comprising a jar having an externally threaded neck, a bracket for supporting the jar in upright inverted position, said bracket including a 115 horizontal supporting member, a cap for the jar including an annular flange for removable attachment to said horizontal supporting member, said flange being threaded to fit said neck, a spout issuing from the 120 cap, a valve member for obstructing the flow of liquid from said spout and means for actuating said valve member.

In testimony whereof, I have signed my name to this specification.

ARCHIE M. SUND.
